UNITED STATES PATENT OFFICE.

CARL HOLMSTRÖM, OF WESTMINSTER, LONDON, ENGLAND; KATHERINE ANNÉTE HOLMSTROM EXECUTRIX OF SAID CARL ALBERT HOLMSTRÖM, DECEASED.

BREECH-LOADING ORDNANCE.

1,273,860.

Specification of Letters Patent. Patented July 30, 1918.

Application filed November 3, 1914. Serial No. 870,003.

To all whom it may concern:

Be it known that I, CARL HOLMSTRÖM, a subject of the King of Great Britain, residing at 8 The Sanctuary, Westminster, in the county of London, England, have invented certain new and useful Improvements in or Relating to Breech-Loading Ordnance, of which the following is a specification.

This invention relates more particularly but not exclusively to breech loading ordnance of the kind set forth in the specification of British Patent No. 933 of 1906, in which the breech screw after having been angularly displaced to unlock it is moved rearwardly in the swinging carrier in a rectilinear path by means of a pair of cranks or pivoted arms mounted on the carrier at a point behind the breech screw and adapted to coöperate with flanges or cam grooves on the face of the screw to exert a powerful rearward pull or toggle-like action. The said cranks or pivoted arms may be moved by an operating rack which is formed with a groove for the reception of a guide bolt carried by a pivoted lock frame, the said groove thus serving to rock the lock frame to and from its open position; this arrangement is set forth in the specification of British Patent No. 11111 of 1906.

According to my present invention I employ a tube or primer loading device which comprises in addition to the known movable primer carrier, a displaceable primer actuating member which serves when moved in the proper direction to permit or effect the movement of the primer carrier into a position opposite the axial vent, further movement of the said member then pushing a primer from the carrier into the primer chamber of the axial vent. Movement of the primer actuating member in the opposite direction first causes it to be displaced outwardly relatively to the primer carrier and to then move the latter into a position convenient for enabling a new primer to be inserted. The lock frame may be left in the partly open position when the breech mechanism is closed (*i. e.* in a position in which the lock frame resiliently overlaps the primer chamber of the axial vent in order to retain the primer in place after its insertion as will be understood by reference to the aforesaid British Patent No. 11111 of 1906 and to the earlier British Patent No. 15364 of 1901 referred to in the said British Patent No. 11111 of 1906),

and means are provided whereby the closing of the lock frame may be effected by the displacement of the primer carrier to its inoperative position.

The portion of the groove in the operating rack that engages with the guide bolt when the breech mechanism is closed and locked is so formed that when the breech mechanism is closed and locked the lock frame remains in its partly open position as aforesaid.

It has heretofore been usual to insert a new primer when the breech is open or partly open, but in the arrangement described above it is desirable to prevent a primer from being inserted unless the breech mechanism is closed and locked; with this object in view the portion of the groove of the operating rack that engages with the guide bolt after the lock frame has been caused to overlap the primer chamber, is made of the same width as the diameter of the guide bolt and so arranged that the lock frame is firmly retained in its overlapping position.

In order that the said invention may be clearly understood and readily carried into effect I will describe the same more fully with reference to the accompanying drawings in which:—

Figures 1, 2 and 3 are a rear elevation, a sectional plan and a side elevation of a portion of the breech screw carrier showing a constructional form of the invention.

Figs. 4, 5 and 6 are sections taken approximately on the line 1, 1 of Fig. 1 showing the primer carrier and its associated parts in three different positions.

Figs. 7 and 8 are rear elevations showing the lock frame in two different positions.

Fig. 9 is a rear elevation of the operating rack showing the preferred form of the groove therein, and

Fig. 10 is a section taken longitudinally through the guide bolt.

In these figures A is the breech screw carrier, B the lock frame, B' the box slide, B² the guide bolt carried by the lock frame, C the operating rack and C' the groove therein for engaging with the guide bolt. D represents the primer carrier and E the primer actuating member.

In the example shown the primer carrier D is loosely mounted on a spindle D' which is supported in a bracket A' on the breech screw carrier and which is arranged trans-

versely to the gun above the lock frame and to this shaft is keyed or otherwise connected the primer actuating member E. This member is in the form of an arm having a cam 5 slot E' for the reception of a pin e' carried by a plunger e slidably mounted in the primer carrier D. The primer carrier D has spring controlled jaws d, d which resiliently hold the primer in its central position so 10 that it can be properly inserted into the primer chamber when the primer carrier assumes its lowermost or primer charging position. The said carrier also has a spring controlled retaining catch d' which normally 15 (i. e. until the carrier reaches the position shown in Figs. 5 and 6) coöperates with the forward end of the primer in the carrier and prevents it from being displaced by any pressure exerted on the base by the plunger 20 e. The retaining catch d' is adapted to be displaced into the position shown in Figs. 5 and 6 by a slide d² which by its coöperation with an incline b' on the box slide B' displaces the slide to rock the catch about its 25 pivot into the disengaging position. Further movement of the arm E then forces the primer into its chamber in the vent axial. The slide d² is prevented from moving as above indicated until the carrier is in the position shown by Figs. 5 and 6, by a portion 30 of the bracket A' which is cut away as indicated at a' to permit this movement to take place when the parts are in the position shown. This portion of the bracket A' acts 35 as a cam which serves to return the slide d² to its original position when the carrier is being raised and to cause the retaining catch d' to nip and extract the primer in the event of its not being fully inserted, thereby preventing jamming of the parts during the 40 closing of the frame.

The transverse spindle D' is controlled by a helical or other spring D² (Fig. 2) normally serving to retain the carrier D in its 45 raised position and is provided at its outer end contiguous to the hinge pin of the breech screw carrier, with a handle D³ so that this spindle can be actuated while the operator occupies a position out of the path 50 of recoil of the gun.

It will be observed from Figs. 1 and 4 that the primer carrier normally occupies a position in which the primer or primers are not in alinement with the vent but at a con- 55 siderable angle thereto, so that in the event of accidental ignition of the primer taking place the flash cannot enter the vent.

The lock frame, as will be hereinafter described, is left in the partly open position 60 (that is, a position in which it is caused by a spring plunger B^x (Fig. 1) to resiliently overlap the primer chamber) during the closing of the breech mechanism and during the lifting of the primer carrier is closed by 65 a member E² operated by the aforesaid

transverse spindle. This member in the example shown has the form of an arm hinged at e² to the bracket A' and is operated by bevel gearing from the said spindle. The outer end of this arm is adapted, during 70 its upward movement and the upward movement of the carrier D, to engage with the lock frame and displace it to the closed position and the said outer end carries a spring plunger or bolt which, by its cooperation 75 with an inclined surface on the lock frame, enables the arm to move downward after the lock frame has been opened.

Referring more particularly to Figs. 7 to 10 in which the rack C is illustrated it will 80 be seen that, assuming the rack to be one that moves from left to right during the opening of the breech mechanism, the left hand portion c' of the groove C' is made of the same width as the diameter of the guide 85 bolt B². The portion c' of the groove thus serves to positively hold the lock frame in the overlapping position shown in Fig. 7 when the breech mechanism is open and thereby prevents a primer from being inserted. In order to enable the lock frame to remain in the partly open position during the closing of the breech mechanism the right hand portion of the groove may be enlarged and formed with an incline c² terminating in a flat c³ upon which the guide bolt 90 B² rests when the breech mechanism is fully closed and locked and from which it can be displaced by hand after the insertion of a primer in order to permit it to move from 95 the said flat and to enter the extreme right hand portion of the groove, this portion being at a lower level than the said flat to form a shoulder c⁴ which prevents the guide bolt from moving with the lock frame in the 100 opening direction without the guide bolt having first been withdrawn. In this manner the lock frame is held in such a position that the firing pin or striker is in alinement with the axis of the vent chamber thereby 105 preventing misfires from taking place due to an incorrect position of the firing pin. During the closing of the breech the guide bolt bears against the upper wall of the straight portion of the groove, falls into the de- 110 pressed portion c^{5x} and then mounts the incline c² as aforesaid. During the opening of the breech the guide bolt engages in the inclined or curved portion c^{6x} of the groove and then passes by an inclined part c^{2x} into 115 the left hand end of the groove. The shoulder c⁴ serves to move the lock frame to its overlapping position.

It is possible that the coöperation of the aforesaid incline c² with the guide bolt may 120 move the lock frame toward its closed position, and in order to prevent any such possibility the lock frame is shown as provided with a projection or spring plunger b² (Figs. 7, 8 and 10) which engages with the under 125

side of the operating rack C during the closing of the breech mechanism. The operating rack is suitably grooved or slotted at c^5 to accommodate the spring plunger; 5 another plunger b^2 (Fig. 10) may if desired be arranged above the guide bolt in addition to or in substitution for the above mentioned plunger b^2 . For the accommodation of this plunger the rack is grooved or 10 slotted at c^5 .

What I claim and desire to secure by Letters Patent of the United States is:—

1. In breech loading ordnance, the combination with the breech screw carrier, of a 15 primer carrier and a primer actuating member, both movable in the same direction and in a curvilinear path relatively to the breech screw carrier, and means for moving said member to effect the movement of the carrier into a position opposite the primer chamber of the axial vent and to then insert a primer from the carrier into the primer chamber.

2. In breech loading ordnance, the combination with a pivoted primer carrier, of a 25 primer actuating member pivoted to move about the same axis as the carrier, and means for moving said member to effect the movement of the carrier into a position opposite the primer chamber of the axial vent and to then insert a primer from the carrier into the primer chamber.

3. In breech loading ordnance, the combination with the breech screw carrier, of a 35 movable primer carrier and a primer actuating member both movable in the same direction and in a curvilinear path relatively to the breech screw carrier, a device for retaining the primer in position in the carrier, and means for displacing this retaining device as the carrier assumes a position opposite the primer chamber of the axial vent.

4. In breech loading ordnance, the combination with a primer carrier, a shaft on 45 which this carrier is loosely mounted, an arm rigidly mounted on said shaft, a device for retaining the primer in position in the carrier and means for displacing this retaining device as the carrier assumes a position opposite the primer chamber of the axial vent.

5. In breech loading ordnance, the combination with the lock frame of a device movable independently of the lock frame for inserting primers into the primer chamber of the axial vent, and means also movable independently of the lock frame for extracting the primer from this chamber in the 55 event of its not having been fully inserted therein.

6. In breech loading ordnance, the combination with the lock frame of a primer carrier movable independently of the lock 60 frame and a device for inserting primers

from this carrier into the primer chamber of the axial vent, of means mounted in said carrier for extracting the primer from this chamber during the movement of the carrier to its inoperative position, in the event 70 of this primer not having been fully inserted.

7. In breech loading ordnance, the combination with a movable primer carrier, of a primer actuating member, a device for retaining the primer in position in the carrier, means for displacing this retaining device as the carrier assumes a position opposite the primer chamber of the axial vent, and means for causing said device to engage 75 with the primer in the event of its not having been properly inserted in its chamber and to extract the said primer during the movement of the primer carrier to its inoperative position.

8. In breech loading ordnance, the combination with the lock frame, of a movable device for inserting a primer into its chamber in the axial vent, means for leaving the lock frame in the partly open position when the breech mechanism is locked and means, dependent upon the displacement of the said device to its inoperative position, for shifting the lock frame to its closed position.

9. In breech loading ordnance, the combination with the lock frame, of a movable primer carrier, manual means for moving said carrier to and from its operative position opposite the primer chamber of the axial vent, means for leaving the lock frame in a partly open position when the breech mechanism is closed and a member, operated by said manual means, for closing the lock frame when the primer carrier is being moved to its inoperative position.

10. In breech loading ordnance, the combination with the lock frame, of a spring 110 operating upon said lock frame when the latter is in the open position, a grooved member, actuated by the breech mechanism, for operating the lock frame, the groove in this member being so formed that the lock frame is opened during the opening of the breech mechanism and is released when the breech mechanism is locked so that the spring operating on the lock frame can move the latter to a position overlapping the primer chamber.

11. In breech loading ordnance, the combination with the lock frame, of a spring 120 operating upon said lock frame when the latter is in the open position, a guide bolt carried by the lock frame, a member operated by the breech mechanism and having a groove for the reception of the guide bolt, said groove being so formed that the lock frame is opened during the opening of the breech mechanism and is released when the breech mechanism is locked so that the spring operating on the lock frame can move 125 130

the latter to a position overlapping the primer chamber.

12. In breech loading ordnance, the combination with the lock frame, of a guide bolt carried by the lock frame, a member operated by the breech mechanism and having a groove for the reception of the guide bolt, said groove being so formed that the lock frame is opened during the opening 10 of the breech mechanism and is left in the partly open position when the breech mechanism is locked, and means for positively preventing the lock frame from being displaced from this position until the breech 15 mechanism is locked.

13. In breech loading ordnance, the combination with the lock frame, of a guide bolt carried by the lock frame, a member operated by the breech mechanism and having a groove for the reception of the guide bolt, said groove being so formed that the lock frame is opened during the opening of the breech mechanism and is left in the partly open position when the breech 20 mechanism is locked, and a projection carried by the lock frame for engaging with the said member for positively preventing the latter 25

from being displaced from this position until the breech mechanism is locked.

14. In breech loading ordnance, the combination with the lock frame, of means for causing the latter to overlap the primer chamber of the axial vent and for positively preventing it from moving from this position when the breech mechanism is fully 30 open, the lock frame thus preventing a primer from being inserted at this time.

15. In breech loading ordnance, the combination with the lock frame, of a guide bolt carried thereby, a member operated by 35 the breech mechanism and having a groove for the reception of the guide bolt, said groove being so formed that the lock frame is positively held in a position to overlap the primer chamber of the axial vent when 40 the breech mechanism is fully open, the lock frame thus preventing a primer from being inserted at this time.

In testimony whereof I affix my signature in presence of two witnesses.

CARL HOLMSTRÖM.
